UNITED STATES PATENT OFFICE.

GEORGE WATKINSON, OF NEW HAVEN, CONNECTICUT, ASSIGNOR TO THE
L. CANDEE & CO., OF SAME PLACE.

DESIGN FOR OVERSHOES.

Specification forming part of Design No. 6,986, dated November 4, 1873; application filed June 27, 1873.
[Term of Patent 7 years.]

To all whom it may concern:

Be it known that I, GEORGE WATKINSON, of New Haven, in the county of New Haven and State of Connecticut, have invented a new Design for Overshoes; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for the construction of overshoes; and it consists in the peculiar shape of the shoe, as shown in

the accompanying illustration, and as more fully hereinafter described.

The peculiar feature of this design is the instep piece A, which extends up over the instep, (the side slit as at B;) thence, by a slight and single curve, up to a high heel, all as shown in the accompanying illustration.

I claim as my invention—

The design for overshoe, as shown in the accompanying illustration, and as herein described.

GEO. WATKINSON.
